Term of patent 14 years

Int. Cl. D5—06

U.S. Cl. D59—2 B

FIG. 1.

FIG. 2.

FIG. 1 is a plan view of two paper towel sections showing my new design, a full width of the design being shown with the design unit being repeated in regular succession to an indeterminate length, the design being shown only in the lower left-hand and upper right-hand corners for convenience of illustration.

FIG. 2 is an enlarged plan view of the design shown in FIG. 1, the background embossed or dimpled configuration of the background having been omitted for convenience of illustration.

I claim:

The ornamental design for paper toweling, as shown and described.
